SUPERHEATER BOILER

David S. Jacobus, Montclair, N. J., and William A. Jones, West New Brighton, N. Y., assignors to The Babcock & Wilcox Company, Bayonne, N. J., a corporation of New Jersey

Application December 1, 1925, Serial No. 72,423

40 Claims. (Cl. 122—303)

This invention relates to a steam boiler which has superheaters or reheaters, and will be understood from the description in connection with the accompanying drawings, in which Fig. 1 is a vertical section through an illustrative form of boiler embodying the invention; Fig. 2 is a similar section on an enlarged scale showing the upper portion of Fig. 1; Fig. 3 is a plan view, partly in section, of a part of Fig. 2, showing the water circulators and their connections to the headers and the steam and water drum; Fig. 4 is a front elevation of Fig. 3, partly in section, showing the secondary superheater; Fig. 5 is an enlarged view in elevation showing how the secondary superheater headers are supported; Fig. 6 is a side elevation, on an enlarged scale, showing the secondary superheater tube supports; Fig. 7 is an end view of Fig. 6; Fig. 8 is a plan view of the same; Fig. 9 is a side view showing a part of one of the details; Fig. 10 is a side view of a metal plate for holding the tile of one of the baffles shown in Fig. 1, and Fig. 11 is a section along the line 11—11 of Fig. 10.

Like reference characters indicate like parts in the different views.

In the drawings, reference character 10 indicates the furnace of a boiler in which an underfeed stoker 11 is located. A bank of inclined tubes 12 of the boiler proper is connected to headers 14 and 15 and a second bank of inclined tubes 13 of the boiler is connected to headers 16 and 17, the headers 14 and 16 being connected by nipples 18 and the headers 15 and 17 being connected by nipples 19. Nipples 21 connect the headers 16 to the steam and water drum 23, the upper ends of alternate nipples being bent in one direction, and the remainder in the opposite direction, to enter the drum 23 in two parallel rows, as indicated. Nipples 22 connect the headers 17 to the headers 24. A feed water inlet 25 for the drum 23 is shown and a steam outlet 26 from the drum leads to the header 27 of the primary superheater 28. The tubes of this superheater have a reverse bend and are connected to the outlet header 29.

A baffle 31 is placed near the lower end of the bank of tubes 12 along the upper side of the bank and a plurality of supports 32 for the superheater 28 is mounted upon these tubes. A baffle 33 prevents contact of the hot gases with the header 27 and a similar baffle 34 prevents contact of the gases from the first upward pass with the header 28.

A flat suspended arch of tile 44 extends above part of the length of the superheater tubes 28,

the tile being supported on a plurality of metal plates 35, each having one end supported on clips on nipples 18 and the other bolted to a fin 30 integral with header 29. An upwardly extending fin 30' on the header 29 is similarly bolted to the plates forming the transverse baffle 48, these plates having notches along their edges engaging tubes 13 in the same manner that plates 30 engage tubes 60, as hereinafter described.

Each metal plate 35 (Figs. 1, 10 and 11) for holding tile 44 is provided with a flange 36 at one end thereof and a similar flange 37 near the opposite end. Strengthening ribs 38 are provided on the topside of the plate 35 for the rib 37 and a longitudinal strengthening rib 39 extends along the middle of the topside of the plate 35 from the flange 36 to the flange 37. A transverse flange 40 extends across the lower side of the plate 35 and a strengthening rib 41 is provided therefor. A bulbed rib 42 extends longitudinally of the plate 35 on the lower side thereof from the flange 40 to the end of the plate. This bulbed rib is provided with a beaded edge 43 engaging grooves in the tile 44 to hold the same in position in the well-known way. The arch is inclined and the horizontal thrust of the rows of tile 44 is against the flanges 40.

A baffle 48 is provided with a seat 49 along its upper edge for the lower movable baffle plate that is to be described later. Another baffle 50 extends across the bank of tubes 13, from the upper edge of which a baffle wall 51 extends to the lower side of a bank of circulating tubes 55. A baffle 52 extends across the bank of circulating tubes to the roof 53, and a gas outlet is shown at 54. The bank of circulating tubes 55 connects the steam and water drum 23 to the headers 24. These tubes 55 enter the drum 23 radially along circumferential lines, the lowest tubes being straight and the others being slightly bent at the ends where they enter the drum 23. The other ends of these tubes 55 are offset longitudinally of the drum 23, as shown in Fig. 3, so that the alternate ones in a vertical row enter adjacent headers 24 and 24'. By the arrangement illustrated, each header is connected to the drum by a pair of tubes and yet the tube holes are spaced along the drum so as to give a greater ligament strength than if the tubes were arranged with the spacing of the tubes longitudinally of the drum the same as the spacing of the headers. It will be understood that a continuous water box may be used instead of the separate headers illustrated, such a set of headers or a continuous water box constituting an uptake water chamber.

45
50
55

It will be understood therefore, that when I refer in the claims to a row of water chambers arranged in a row extending longitudinally of the drum, I intend to cover continuous water boxes.

5 A heat transfer device which, in the embodiment illustrated, is a secondary superheater or reheater is divided into two sections or portions and is located near the circulating tubes 55. This reheater comprises cylindrical headers connected by tubes extending at right angles to the boiler tubes. The header 58 of the reheater is provided with a steam inlet 59 and a bank of tubes 60 extends from header 58 to the header 61 on the other side of the boiler and located in a higher 10 plane than the header 58. Tubes 60 are connected to the upper side of the header 58 along and on both sides of the central longitudinal line thereof, and extend to the lower side of the header 61 to which they are connected in a manner 15 similar to the way they are connected to the upper side of header 58. These tubes are bent in vertical planes near their ends, so that the medial portions thereof will be horizontal, each tube being somewhat S-shaped. A steam pipe 62 connects the header 61 to the header 63, which is located at the same level as the header 58, and is displaced longitudinally of the headers 58 and 61, as shown in Fig. 5. A bank of tubes 64 similar to the bank of tubes 60 connects the 20 header 63 to the header 65, similar to the way headers 58 and 61 are connected. The header 65 is likewise displaced longitudinally of the headers 58 and 61 and is on the same level as the header 61. A steam outlet 66 is connected to the 25 header 65. Beams 69 extend above the top of the boiler from front to rear, and I-beams 70 and channel bars 71 are laid transversely across the same. Straps 72, 73, 74 and 75 extend from the channel bars 71 around the headers 65, 63, 61 and 30 58 respectively, and support the same, nuts being screwed on to the threaded upper ends of these straps to adjust the headers to the proper positions. Supporting rods 78 extend from the I-beams 70 and are connected to metal bars 79 35 (Figs. 2, 6, 7 and 8) to which metal supports 80 for tubes 60 and 64 are fastened on opposite sides thereof by means of bolts 81 in staggered relation. The supports 80 are provided with recesses 82 along the edges thereof, large enough for the 40 tubes to enter. Bars 83 similar to bars 79 are connected to the supports 80 by bolts 81.

55 Preferably, the tubes in each horizontal row are spaced, as shown, with alternately wide and narrow spaces, so that the wide spaces will permit the passage of a tube in withdrawing and replacing the same, the distance between the tubes at the wide spacing being slightly larger than the diameter of a tube. The supports 80 are correspondingly arranged to support the tubes as thus spaced, each of the supports 80 on one side of the metal bars 79 coming between a pair of narrowly spaced tubes, and each of the supports 80 on the other side between a pair of widely spaced tubes.

60 65 By having supports 80 alternately on opposite sides of bars 79, they may be more readily attached to bars 79 and may more readily be turned into and out of position between a pair of vertical rows of tubes.

70 75 The upper and lower bars 79 and 83 with their connected supports 80 constitute a relatively stiff support for the tubes of the secondary superheater and yet one which can be readily constructed after the tubes are in place, each of the supports 80 being passed through an aisle formed

between a pair of vertical rows of tubes and then turned into position with each of its recesses 82 surrounding a tube, and the support is then bolted in place to the bars 79 and 83.

5 A movable baffle 85 (Figs. 1, 2 and 4) is located parallel with and between the two sets of tubes 60 and 64. This baffle is provided with notches or recesses 86 along its upper edge to permit it to be raised among the tubes 55, as most clearly shown in Fig. 4. The lower ends of the lifting 10 rods 87 are attached to the baffle 85 and pass through the roof 53 of the boiler setting, and are connected to the elevating mechanism 88 which is supported on channel irons 89 that rest upon the beams 69. A shaft 90 driven from any convenient source operates the mechanism for raising and lower the rods 87.

15 In operation, hot gases from the furnace 10 (see Fig. 1) pass upwardly into contact with the lower bank 12 of inclined water tubes and across the same into contact with the long ends of the superheater tubes 28, being prevented from contacting with the header 27 of said superheater by means of the baffles 31 and 33. The baffle 44 deflects the gases so that they pass across the short ends of 20 the superheater tubes 28, being prevented from contacting with the header 29 by means of the baffle 34. The gases then pass across the bank of tubes 13 between the baffle 48 and the headers 17, thence, when the baffle 85 is in its lowermost 25 position, across the set of reheater tubes 64, thence longitudinally along the circulating tubes 55 over the top edge of the baffle 85, thence downwardly across the set of reheater tubes 60 and across the bank of tubes 13, under the lower 30 edge of the baffle 50, across the ends of the circulating tubes 55 and to the outlet 54. When the baffle 85 is raised to leave a space between its lower edge and the upper edge of the baffle 48, a portion of the gases passes through this space 35 without contacting with the tubes 64 or 60. The higher the baffle 85 is raised, the more of the gases pass across through this space, so that the amount of heat absorbed by the reheater tubes 60 and 64 can be regulated. In Fig. 2, the baffle 40 45 50 55 60 65 70 75 80 85 is shown in its highest position and in Fig. 1, in its lowest position with its lower edge resting on the seat 49, baffle 85 in the position of Fig. 1 forming a continuation of baffle 48. It is noted that the steam entering reheater header 58 and passing first through the set 60 of tubes and later through the set 64 of tubes flows in a generally 50 55 60 65 70 75 80 85 90 95 100 105 9685 9690 9695 9700

headers would then necessitate the spacing of the two sets of tubes 60 and 64 relatively widely apart, which the arrangement illustrated avoids.

By providing the separate supports for the headers and the tubes of the secondary superheater or reheater, a maximum freedom of motion for the various parts is permitted while, at the same time, providing adequate support for each part. Each header is free to move independently of the other headers and the tubes are free to expand and contract by movement through the recesses 82 of supports 80, the bending of the tubes at each end also permitting difference in expansion in the several tubes without placing undue strain on the connections between the ends of the tubes and the headers.

We claim:

1. In a boiler, a horizontal cylindrical drum, a plurality of vertically disposed headers in a row extending longitudinally of the drum and spaced therefrom, and tubes connecting said headers and said drum, said tubes being arranged in a plurality of horizontal rows, the ends of a pair of tubes, one each from a pair of adjacent horizontal rows, entering the drum on substantially the same drum circumference and the other end of each of said pair of tubes entering respectively one of an adjacent pair of headers, the tubes of each pair entering headers at different elevations.

2. In a boiler, a horizontal cylindrical drum, a plurality of vertically disposed headers in a row extending longitudinally of the drum and spaced therefrom, and tubes connecting said headers and said drum, said tubes being arranged in a plurality of horizontal rows, the ends of a pair of tubes, one each from a pair of adjacent horizontal rows, entering the drum radially on substantially the same drum circumference and the other end of each of said pair of tubes entering respectively one of an adjacent pair of headers, the entrance points in said adjacent pair of headers being at different elevations.

3. In a boiler, a horizontal cylindrical drum, a plurality of vertically disposed headers in a row located longitudinally of the drum and spaced therefrom, and tubes connecting said headers and said drum, said tubes being arranged in a plurality of horizontal rows, the ends of a pair of tubes, one of which is a tube of one of said horizontal rows and another is a tube of an adjacent row of said horizontal rows, entering the drum on substantially the same drum circumference and the other end of each of said pair of tubes entering respectively one of an adjacent pair of headers and each header having at least two of said tubes entered therein.

4. In a boiler, a horizontal cylindrical drum, water chambers arranged in a row extending longitudinally of the drum and spaced therefrom and a plurality of rows of tubes connecting said chambers and said drum, the ends of a pair of tubes each in a pair of adjacent horizontal rows entering the drum in substantially the same drum circumference and the other ends of said pair of tubes being bent in opposite directions and entering said water chambers through openings which are out of either vertical or horizontal alinement.

5. In a water tube boiler, a heat transfer device having a bank of horizontally extending tubes arranged in a plurality of horizontal rows, headers connected to the ends of said tubes, a fixed support above the tubes, and suspension devices for the portion of the tubes between the

headers, comprising a plurality of vertically disposed plates extending across said bank and having recesses along their edges, with one of said tubes in each recess, a top and a bottom horizontal bar respectively above and below said bank and connected respectively to the top and the bottom of said plates, and a plurality of suspension members connecting said top horizontal bar with said support. 5

6. In a water tube boiler, a heat transfer device having a bank of horizontally extending tubes arranged in a plurality of horizontal rows, headers connected to the ends of said tubes, a fixed support above the tubes, and suspension devices for the portion of the tubes between the 15 headers, comprising a plurality of vertically disposed plates extending across said bank and having recesses along their edges, with one of said tubes in each recess, said plates being arranged in a row extending across the bank, with alternate plates out of alinement with the plates at either side and overlapping the edges thereof, whereby each tube is positioned in the oppositely extending recesses of a pair of adjacent plates, and suspension members connecting the tops 25 of said plates with said support.

7. In a water tube boiler, a heat transfer device having a bank of horizontally extending tubes arranged in a plurality of horizontal rows, headers connected to the ends of said tubes, a fixed support above the tubes, and suspension devices for the portion of the tubes between the headers, comprising a plurality of vertically disposed plates extending across said bank and having recesses along their edges, with one of said tubes in each recess, said plates being arranged in a row extending across the bank, with alternate plates out of alinement with the plates at either side and overlapping the edges thereof, whereby each tube is positioned in the oppositely extending recesses of a pair of adjacent plates, a top and a bottom horizontal bar respectively above and below said bank and connected respectively to the top and the bottom of said plates, and a plurality of suspension members connecting said top horizontal bar with said support. 40

8. In a water tube boiler, horizontally inclined water tubes, uptake and downtake water chambers connecting the ends of said tubes, a steam and water drum connected to said chamber, cross baffles to direct the furnace gases back and forth across the water tubes, a heat transfer device above the water tubes and having two banks of tubes side by side and extending across the water tubes in the path of the furnace gases and a header for each end of each of said banks of tubes of said device and connected to the ends of the tubes in a bank, said headers being structurally independent of each other, a fluid outlet and a fluid inlet respectively in the headers of said device at one side of the boiler and a connection between the headers at the other side of the boiler, said inlet, outlet and connection being arranged to cause the fluid to flow in said device first through the tubes contacted by the cooler 55 furnace gases and then through the tubes contacted by the hotter furnace gases, and a vertically disposed and vertically movable baffle between said banks to regulate the flow of gases thereover. 70

9. In a water tube boiler, horizontally inclined water tubes, uptake and downtake water chambers connecting the ends of said tubes, a transverse steam and water drum above the downtake water chambers, substantially horizontal water 75

- circulating tubes extending from said drum to said uptake water chambers, cross baffles to direct the furnace gases back and forth across the water tubes, a heat transfer device having two banks of tubes side by side and extending transversely of the water tubes and between the water tubes and said circulating tubes in the path of the furnace gases, a header for each end of each of said banks of tubes of said device and connected to the ends of the tubes in a bank, said headers being structurally independent, and a vertically disposed and vertically movable baffle between said banks to regulate the flow of gases thereover, said vertically movable baffle being arranged, when in its lowermost position, to direct the gases up over the tubes of one of said banks, through the space through which said circulating tubes extend and then down over the tubes of said second bank.
10. In a water tube boiler, horizontally inclined water tubes, uptake and downtake water chambers connecting the ends of said tubes, a transverse steam and water drum above the downtake water chambers, substantially horizontal water circulating tubes extending from said drum to said uptake water chambers, cross baffles to direct the furnace gases back and forth across the water tubes, a heat transfer device having two banks of tubes side by side and extending transversely of the water tubes and between the water tubes and said circulating tubes in the path of the furnace gases, a header for each end of each of said banks of tubes of said device and connected to the ends of the tubes in a bank, said headers being structurally independent, and a vertically disposed and vertically movable baffle between said banks to regulate the flow of gases thereover, said vertically movable baffle being arranged, when in its lowermost position, to direct the gases up over the tubes of one of said banks, through the space through which said circulating tubes extend and then down over the tubes of said second bank, said vertically movable baffle having recesses in its upper edge to receive said circulating tubes when it is moved to its uppermost position to permit the gases to flow through a portion of one bank directly into a portion of the other bank.
11. In a boiler, upper and lower banks of horizontally inclined water tubes spaced apart to form a superheater chamber therebetween, uptake and downtake water chambers connected to the ends of said water tubes, a superheater in said chamber having headers extending transversely of the water tubes and U-tubes connecting said headers and extending parallel to the water tubes, the legs of said U-tubes being unequal in length with the upper legs the shorter and the header connected to the long legs adjacent one of the water chambers and the header connected to the short legs remote therefrom, and a baffle entirely within said chamber and extending from said water chamber to and supported on the header connected to the short leg of the superheater tubes, said baffle comprising a plurality of metal supports and tile connected to the lower side thereof.
12. In a boiler, upper and lower banks of horizontally inclined water tubes spaced apart to form a superheater chamber therebetween, uptake and downtake water chambers connected to the ends of said water tubes, cross baffles in the upper bank to direct the furnace gases from the superheater chamber back and forth across the water tubes of the upper bank, a superheater in

said chamber having an upper transverse header positioned adjacent the lower edge of the cross baffle separating the first up-pass from the first down-pass across the upper bank of water tubes, a lower transverse header adjacent one of said water chambers, U-tubes with legs of unequal length connecting said headers, and a baffle extending from said upper superheater header to said downtake water chambers, beneath said first downward pass and separated from the upper bank of water tubes and also separated from the longer legs of said U-tubes.

13. In a boiler, upper and lower banks of horizontally inclined water tubes spaced apart to form a superheater chamber therebetween, uptake and downtake water chambers connected to the ends of said water tubes, cross baffles in the upper bank to direct the furnace gases from the superheater chamber back and forth across the water tubes of the upper bank, a superheater in said chamber having an upper transverse header positioned adjacent the lower edge of the cross baffle separating the first up-pass from the first down-pass across the upper bank of water tubes, a lower transverse header adjacent one of said water chambers, U-tubes with legs of unequal length connecting said headers, and a baffle extending from said upper superheater header to said downtake water chambers beneath said first downward pass and separated from the upper bank of water tubes, said baffle being also separated from the longer legs of said U-tubes and having one end supported on said upper header and said upper header being connected to and supported by the cross baffle above it.

14. In a boiler, a cylindrical drum, a plurality of headers arranged in a row extending longitudinally of the drum and spaced therefrom, and tubes arranged throughout their entire lengths in a plurality of rows extending longitudinally of the drum and connecting said headers and said drum, the tubes entering the drum along circumferential lines which are farther apart than the center line distances between the headers, the ends of said tubes being staggered where they enter the headers.

15. In a boiler, a cylindrical drum, a plurality of headers arranged in a row extending longitudinally of the drum and spaced therefrom, and tubes arranged throughout their entire lengths in a plurality of rows extending longitudinally of the drum and connecting said headers and said drum, the tubes entering the drum radially along circumferential lines which are farther apart than the center line distances between the headers, the ends of said tubes being staggered where they enter the headers.

16. In a boiler, a cylindrical drum, a plurality of headers arranged in a row extending longitudinally of the drum and spaced therefrom, and tubes arranged throughout their entire lengths in a plurality of rows extending longitudinally of the drum and connecting said headers and said drum, the tubes entering the drum along circumferential lines which are twice as far apart as the center line distances between the headers, the ends of said tubes being staggered where they enter the headers.

17. In a water tube boiler and its furnace, a heat transfer device having tubes extending across the boiler tubes, said tubes being divided vertically into two banks across which the gases from said furnace flow, headers connected to the ends of the tubes of said heat transfer device with a header at a first side of said boiler con-

- 5 nected through tubes of one bank to a header at the second side of the boiler located at a different elevation than said first header and through which the fluid flows, thence through a connection to a header at said second side of the boiler located at substantially the same elevation as said first mentioned header, and thence through the second bank of tubes to the other header located at said first side of the boiler.
- 10 18. In a water tube boiler and its furnace, a heat transfer device having tubes extending across the boiler tubes, said tubes being divided vertically into two banks located at substantially the same elevation and across which the gases from said furnace flow, headers connected to the ends of the tubes of said heat transfer device with a header at a first side of said boiler connected through tubes of one bank to a header at the second side of the boiler located at a different elevation than said first header, thence through a connection to a header at said second side of the boiler located at substantially the same elevation as said first mentioned header, and thence through the second bank of tubes to the other header located at said first side of the boiler.
- 15 19. In a water tube boiler, a bank of inclined tubes, spaced apart upper circulating tubes, a superheater located between said bank and said circulating tubes, means to pass hot gases over said superheater and steam through said superheater in countercurrent directions, and means to by-pass different portions of said hot gases under different conditions of operation to cause only the remaining portion of said gases to cross said superheater tubes.
- 20 20. In a water tube boiler, a bank of inclined tubes, spaced apart upper circulating tubes, a multiple pass superheater located between said bank and said circulating tubes, means to pass hot gases over said superheater and steam through said superheater in countercurrent direction, and means to by-pass portions of said hot gases under different conditions of operation to cause only the remaining portion of said gases to cross said superheater tubes.
- 25 21. In a water tube boiler, a bank of inclined tubes, spaced apart upper circulating tubes, a superheater located between said bank and said circulating tubes, means to pass hot gases over said superheater and inclined tubes in a plurality of passes and into contact with said circulating tubes between said passes, and means to by-pass different portions of said hot gases under different conditions of operation to cause only the remaining portion of said gases to cross said superheater tubes.
- 30 22. In a water tube boiler, a bank of inclined tubes, spaced apart upper circulating tubes, a superheater located between said bank and said circulating tubes, means to pass hot gases over said superheater and steam through said superheater in countercurrent directions, and means to by-pass a portion of said hot gases so as to cross only a portion of said superheater tubes, said last named means comprising a vertically movable baffle.
- 35 23. In a water tube boiler, a bank of inclined tubes, spaced apart upper circulating tubes, a superheater located between said bank and said circulating tubes, means to pass hot gases over said superheater and steam through said superheater in countercurrent directions, and means to by-pass a portion of said hot gases, said last named means comprising a baffle located near the middle of said superheater and adapted to be moved across said circulating tubes.
- 40 24. In a water tube boiler, a bank of inclined tubes, spaced apart upper circulating tubes, a superheater located between said bank and said circulating tubes, means to pass hot gases over said superheater and steam through said superheater in countercurrent directions, and means to by-pass different portions of said hot gases under different conditions of operation to cause only the remaining portion of said gases to cross said superheater tubes, the tubes of said superheater extending substantially at right angles to said bank of tubes.
- 45 25. In a water tube boiler, a bank of inclined tubes, spaced apart upper circulating tubes, a superheater located between said bank and said upper circulating tubes, means to pass hot gases over said superheater and inclined tubes in a plurality of passes, and means to by-pass different portions of said hot gases under different conditions of operation to cause only the remaining portion of said gases to cross said superheater tubes.
- 50 26. In a water tube boiler, a steam and water drum, horizontally disposed water circulating tubes connected to said drum, a heat transfer device below said tubes having tubes extending transversely of said circulating tubes, a baffle extending between tubes of said heat transfer device, and means for moving said baffle across tubes of said circulating tubes.
- 55 27. In a water tube boiler, a steam and water drum, horizontally disposed water circulating tubes connected to said drum, a heat transfer device below said tubes having tubes extending transversely of said circulating tubes, a baffle extending between tubes of said heat transfer device, said baffle having notches therein, and means for moving said baffle across tubes of said circulating tubes.
- 60 28. A heat transfer device comprising two adjacent banks of tubes, a header to which the tubes of the first of said banks of tubes are connected, said header being located at one end of said banks of tubes outside of the planes bounding the main portions of said tubes, a second header to which the other ends of the tubes of the first bank are connected, said second header being located at the other end of said banks of tubes on the other side of said bounding planes from said first-named header, a third header to which the tubes of the second bank of tubes are connected, said third header being located at the same end of said banks as said second header and on the opposite side of said bounding planes from it, and a fourth header to which the other ends of the tubes of the second bank of tubes are connected, said fourth header being located at the same end of said banks as said first header and on the opposite side of said bounding planes from it, and means to cause fluid to enter said first header and leave said fourth header.
- 65 29. In a heat transfer device, a plurality of banks of tubes having their ends bent in opposite directions, headers to which said tubes are connected so located that there is a pair of headers at each end of said banks, and a pair of headers at each side of said banks, the headers at each end of said banks being displaced longitudinally with respect to each other, the tubes of one bank being connected to a header at each end and a header at each side of said banks, and the tubes of another bank being connected to

headers alternating with the headers of the first bank.

30. In a boiler having two vertically spaced banks of horizontal tubes, the combination with 5 said banks, of a baffle between and parallel to them and spaced from both of them, and supports for said baffle hung from tubes in the upper bank.

31. In a boiler, in combination, a bank of horizontal water tubes, a bar transverse to the water 10 tubes and below them, means supporting said bar and engaging and supported by some of the water tubes, an aligned series of bars parallel to the water tubes and suspended from the first named bar, and fire-resisting blocks suspended from 15 said second-named bars contacting with each other and forming a continuous baffle.

32. The combination set forth in claim 31, 20 said second named bars having longitudinal horizontal opposite flanges along their lower edges, and said blocks being suitably slotted to slip on and hang from said flanges.

33. In a boiler, the combination of two spaced 25 banks of horizontal tubes, rods extending through the upper bank, means to support said rods, said means engaging the top tubes of the upper bank, a bar transverse to the water tubes suspended from the rods in the inter-bank space, a set of aligned bars parallel to the tubes suspended from 30 said first named bar, said second bars having an inverted T-shaped cross section, and fire bricks contacting with each other to form a continuous baffle, said bricks being slotted so as to slip on and hang from said second bars.

34. In a water tube boiler, spaced banks of 35 tubes with a tubular heater therebetween, a furnace on the opposite side of one of said banks from said heater, a baffle extending across said banks and said heater to form a pass for gases from the furnace, said baffle being of less extent 40 lengthwise of the pass than the total distance across said banks and heater and spaces therebetween whereby said gases may flow out of the pass transversely thereof, and means for moving a part of said baffle to vary the location at which 45 said transverse flow out of the pass may take place.

35. In a water tube boiler, spaced banks of 50 tubes with a tubular heater therebetween, a furnace on the opposite side of one of said banks from said heater, a baffle extending across said banks and said heater to form a pass for gases from the furnace, said baffle being of less extent 55 lengthwise of the pass than the total distance across said banks and heater and spaces therebetween whereby said gases may flow out of the pass transversely thereof, and means for moving a part of said baffle in its plane to vary the location at which said transverse flow out of the pass may take place.

36. In a water tube boiler, spaced banks of 60 tubes with a tubular heater therebetween, a fur-

nace on the opposite side of one said banks from said heater, a baffle extending across said last-named bank of tubes and into said heater to form a pass for gases from said furnace extending towards the other bank of tubes, whereby said 5 gases may flow over part of the tubes in said other bank, means to move a portion of said baffle to form an opening in the baffle between the heater and the bank of tubes nearest the furnace.

37. In a water tube boiler, spaced banks of tubes with a tubular heater therebetween, a furnace on the opposite side of one of said banks from said heater, a baffle extending across said last-named bank of tubes and into said heater 15 to form a pass for gases from said furnace extending towards the other bank of tubes, whereby said gases may flow over part of the tubes in said other bank, means to move a portion of said baffle to form an opening in the baffle between said 20 banks of tubes.

38. In a steam boiler, spaced banks of boiler tubes, a primary superheater interposed between 25 said banks, a reheat above said banks, means for passing the gases over said primary superheater and said reheat, means comprising a baffle movable across said reheat for increasing or decreasing the temperature of said reheat without materially affecting the temperature of 30 said superheater, and means for causing the gases to engage all of the superheater tubes across the boiler substantially uniformly under every condition of operation.

39. In a steam boiler, spaced banks of boiler tubes, a primary superheater interposed between 35 said banks, a reheat above said banks, means for passing the gases over said primary superheater and said reheat, means comprising a baffle movable across said reheat for increasing or decreasing the heat applied to said reheat 40 without materially varying the heat applied to said superheater, and means for causing the gases to engage all of the superheater tubes across the boiler substantially uniformly under every condition of operation.

40. In a steam boiler, spaced banks of horizontally extending boiler tubes, a primary superheater interposed between said banks, a reheat above said banks, means for passing the gases over said primary superheater and said reheat, 50 means comprising a baffle movable across said reheat for increasing or decreasing the temperature of said reheat by varying the flow of gases thereover without materially changing the flow of gases over said superheater, and means for causing the gases to engage all of the superheater tubes across the boiler substantially 55 uniformly under every condition of operation.
